DIFFERENTIAL CAN FEED MECHANISM

Filed June 21, 1927

Fig. 1.

UNITED STATES PATENT OFFICE

HENRY L. GUENTHER, OF LOS ANGELES, CALIFORNIA

DIFFERENTIAL CAN-FEED MECHANISM

Application filed June 21, 1927. Serial No. 200,352.

This invention relates to differential can feed mechanisms and is more particularly directed to mechanism for feeding cans at high speed to a double seaming mechanism, the cans' bodies being filled with fruit, vegetables or other materials.

The principal object of this invention is to provide a differential can feed mechanism which is adapted to operate at high speed, and which mechanism includes means for timing and accelerating the cans that are delivered to the mechanism, and feeding in same in definite timed relation to a transfer rotor or carriage of a double seaming mechanism. This invention is an improvement over the can feeding and timing device disclosed in patent issued to myself, No. 1,463,527, granted July 31, 1923.

In accordance with this invention, the timing and accelerating of the cans is accomplished entirely on one revolving turret on which the cans are first spaced as they are delivered from any suitable or desirable form of mechanism, and then accelerated to deliver the same to the revolving disc or carriage of a double seaming machine.

Another object of this invention is to provide a differential can feed mechanism including a revolving turret to which the filled cans are delivered, and which revolving turret includes means resiliently held in position for guiding the cans, means for spacing or timing the cans as they are guided, and means operated in conjunction with the revolving turret for accelerating the rate of travel of the cans as the same leave the revolving turret.

Another object of this invention is to provide a differential can feed mechanism including a revolving turret or disc mounted on a driving shaft, and over which disc a star wheel or cam is mounted to space or time the cans fed to the revolving disc, and accelerating means operatively driven by the aforesaid shaft to accelerate the feeding of the cans in timed relation to a capping machine. The acceleration is effected so as to provide a uniform speeding up of the travel of the cans on the revolving turret or transfer disc so as to avoid spilling or

slopping of the cans' contents. The entire timing and accelerating means with the transfer disc is mounted on or grouped around a single shaft so that in our operation the cans are spaced, timed and accelerated thereby permitting the operation of the double seaming machine and feeding mechanism at increased speed.

Other objects and advantages of this invention will be apparent from the following detailed description of a preferred embodiment thereof, as illustrated in the accompanying drawings.

In the drawings:

Figure 1 is a top plan view of a differential can feed mechanism embodying this invention, illustrating the same as attached to and connected with a fragment of a double seaming machine.

Figure 2 is a sectional front elevation thereof.

In the preferred embodiment of this invention illustrated in the accompanying drawings, 1 illustrates the carriage of the double seaming mechanism to which the filled cans are to be delivered. Means are provided adjacent the double seaming mechanism 1 for delivering the cans to the mechanism 1 in timed relation, which means are preferably of the following construction:

A frame 2 supports vertical bearings 3 and 4 within which a vertically extending shaft 5 is journaled. Secured to the shaft 5 is a star wheel 6 which provides a plurality of arcuate segments 7 in which the cans, properly timed, are carried and transferred to the double seaming machine 1.

The star wheel 6 may be of any suitable or desirable construction, such as is ordinarily provided in connection with double seaming mechanisms. Operably mounted in connection with the star wheel 6 is a safety can top feed mechanism 8 which is specifically described and claimed in a patent issued to myself, No. 1,454,383. Operably mounted in connection with the star wheel 6 is a second safety mechanism 9 for arresting the operation of the double seaming machine 1 when a can is not fed to the star wheel 6 by the tim-

ing and accelerating means embodying this invention. The safety mechanism 9 is specifically disclosed and described in a patent issued to myself, No. 1,545,140.

The timing and accelerating mechanism embodied in this invention includes a shaft 10 which is supported in bearings 11 and 12 and which is driven from the shaft 5 by means of a gear 13 which is secured to the shaft 5 and meshes with a pinion 14 carried on a shaft 15 mounted in a bearing 16. Mounted on the shaft 15 is a gear 17 which drives the pinion 18 secured to the shaft 10.

Secured to the frame of the double seaming mechanism, as illustrated at 19, is a bracket 20 which supports at its outer end a pin 21 upon which gears 22 and 23 are secured. The gear 23 meshes with a gear 24 secured to the shaft 10, and the gear 22 meshes with a pinion 25 which is carried by or formed integral with a sleeve 26 which is mounted on the shaft 10. The sleeve 26 is secured, as illustrated at 27, to a horizontally disposed transfer disc 28. The gears and pinions 22, 23, 24 and 25, are of such sizes that as a result the disc 28 is rotated at a speed differing from the speed of the shaft 10. The transfer disc 28 is supported in horizontal position against endwise motion of the shaft 10 by its hub 29 engaging upon the upper surface of the bearing 12.

Mounted adjacent the periphery of the transfer disc 28 is a guide rail 30 which is usually held in position by means of a spring 31 mounted upon a pin 32 which extends through a boss 33 formed in the guide rail casting 34. The guide rail 30 is pivotally supported by the casting 34 at a pin 35 a predetermined distance from a timing cam or star wheel 36. The casting 34 is supported at a bolt 37 to the bracket 20 and at a bolt 38 to the frame of the double seaming mechanism 1. The casting 34, as the same extends beyond the guide rail 30, provides an additional guide rail 39 around the periphery of the transfer disc 28, which is mounted on the shaft 10. The casting 34 extends on its inner end under the star wheel 6 to guide the cans 40 into position relative to the segments 7 of the star wheel 6.

Pivottally mounted in the pin 41 is a trip lever 42 which is operably connected with the can top feed and safety mechanism 8, which is specifically described in Patent No. 1,454,383, heretofore referred to.

The cans 40 are delivered to the transfer disc 28 by any suitable form of mechanism such as a conveyor (not shown), so as to insure the delivery to the transfer disc 28 of a supply of cans 40 at all times.

In order to permit the timing and accelerating means embodying this invention to be operated upon cans of varying diameters, the star wheel 36 is formed of a ring 43 which is removably secured to the flange 44 of the

collar 45, and is provided on its periphery with engaging recesses 46 which approximate closely the particular diameter of the can 40 to be operated upon. In case it is desired to employ timing and accelerating means on cans of different diameters, the ring 43 is changed to accommodate these cans. The collar 45 is preferably secured to the shaft 10.

Means are provided for accelerating the travel of the cans on the transfer disc 28, which means are preferably of the following construction:

Secured to the flange 48 of the collar 45 are brackets 49 on which accelerating fingers 50 are pivotally supported by pins 51. The accelerating fingers 50 are curved outward approximately horizontally, as illustrated at 52, to provide engaging fingers which engage the cans 40 on their rear surface and drive the same along as they travel to the periphery of the transfer disc 28, following the guide rails 30 and 39, and thereby accelerating the travel of the cans 40 as the same move outward toward the periphery of the transfer disc 28.

Cam means are provided for actuating the fingers 50 and are preferably of the following construction:

Journaled to the upper end of the shaft 10 is a stationary cam guide member 53 which is provided with a cam race 54, within which rollers 55 secured to the upper ends 56 of the fingers 50 are mounted, so that the cam race 54 causes the fingers 50 to pivot on the pins 51 to recede from engaging position as the cans are moved onto the transfer disc 28 and are engaged within the recesses 46 of the star wheel 36, and so as to move the fingers outwardly between the cans 40 to engage the rearward surfaces of the cans 40 as the same find their positions within the recesses 46 of the star wheel 36, and so as to cause the cans 40 to move along the guide rail 39 after the same have moved outward away from the timing disc 36, whereby continuing the timed travel of the cans 40 and accelerating the same as they are moved outwardly upon the disc 28.

Mounted over the disc 28 is a second guide rail 57 which engages the inner periphery or surface of the cans 40 and causes the same to travel a path toward the periphery of the transfer disc 28, and this guide rail 57 extends around the periphery of the star wheel 6 so as to guide the cans as the same are engaged within the segments 7.

The cam guide member 53 is rigidly supported in position, as illustrated at 58, by a bracket 59 and is journaled on the upper end of the shaft 10. The sleeve 45 is secured to shaft 10.

Mounted adjacent the entrance end of the can path as the cans are caused to pass into position to be engaged in the segments 7,

is a trip lever 60 which is connected with a control mechanism of the double seaming mechanism 1 as is fully set forth in my Patent No. 1,454,140, heretofore referred to.

5 Means are provided for adjusting elevation of the transfer disc 28 so as to adjust the same in relation to the star wheel 6, which means are preferably of the following construction:

10 The bracket 20 is mounted at 19 so as to permit vertical adjustment of the same by having the bolts pass through slots formed in the bracket 20 and screw-threaded through a boss 61. Threadedly mounted in the base 15 plate 62 is a bolt 63 which engages the lower edge 64 of the bracket 20, so that by screw-threading the bolt 63 in or out, the vertical position of the bracket 20 may be adjusted, and as the transfer disc 28 is supported on 20 the upper edge of the bearing 12 provided by the bracket 20, the position of the transfer disc 28 will be adjusted.

The operation of the differential can feed mechanism embodying this invention is:

25 Cans 40 are fed along the rail 30 to the transfer disc 28 in any suitable or desired manner. Each can 40 is then picked up by the transfer disc 28 and being engaged by the star wheel 36 is spaced from the next can 30 fed into the machine. The travel of the cans 40 is then accelerated as the same are driven and spaced or timed by the star wheel 36 by the engagement of the cans 40 by the accelerating fingers 50. The cans 40 are then 35 driven by the accelerating fingers 50 between the rails 34 and 57 gradually toward the periphery of the transfer disc so that their speed of travel is accelerated. The entire timing, spacing and accelerating means 40 are driven from the shaft 10 so that the cans are timed, spaced and accelerated as the same are driven over the single disc 28.

It will be obvious from the foregoing that I have combined into one single mechanism, 45 means for timing the travel of the cans 40 and means for accelerating the timed travel of the same so that the same will be delivered at an accelerated rate and in timed relation to the star wheel 6, by means of which the 50 same are transferred to the double seaming machine or mechanism 1. The combining of the two means, that is, the means for timing and the means for accelerating the travel of the timed cans into a mechanism, enables me 55 to operate this mechanism at a greater rate of speed so that the cans may be fed to the double seaming machine 1 at a greater rate of speed, thereby increasing the capacity of the machine 1, which is essential to the economic packing or canning of food stuff and 60 the like.

Having fully described the preferred embodiment of my invention, it is to be understood that many changes may be made in 65 the details thereof without departing from

the spirit of my invention as defined by the appended claims.

I claim:

1. In a device of the class described, the combination of a transfer disc, a shaft for driving the transfer disc, a star wheel secured to the shaft over the transfer disc, a plurality of accelerating fingers, means for pivotally supporting the accelerating fingers and for securing the same to the shaft, and means supported in stationary position and providing a cam race for actuating the accelerating fingers. 70

2. In a differential can feed mechanism the combination of a shaft, means for driving the shaft, a transfer disc journaled on the shaft, a star wheel mounted over the disc and driven by the said shaft, accelerating means mounted over the disc and actuated from the said shaft and means for driving the transfer disc at a different speed than said accelerating means and star wheel. 80

3. In a differential can feed mechanism for feeding cans at high speed to a can capping machine, the combination of a shaft, means for driving the shaft, a transfer disc driven from the shaft, a star wheel mounted over the disc and driven from the shaft, said star wheel disc including a removable ring having engaging recesses formed in its periphery, and accelerating means mounted over the disc and actuated from the shaft. 90

4. In a device of the character described, the combination of a drive shaft, a disc, a yieldable guide-rail around a portion of the edge of the disc, a star wheel having a removable portion provided with engaging recesses in its periphery positioned above the disc and adapted to space cans along said guide-rail, a plurality of pivoted accelerating means, means connecting said star wheel and accelerating means, a stationary cam member adapted to co-operate with said accelerating means, means for driving said accelerating means and star wheel from the drive shaft and means for driving the disc from the shaft at a speed different from the speed of said accelerating means and star wheel. 100

5. In a can feeding and timing mechanism, the combination of a driven shaft, a sleeve rotatably mounted on said shaft, a disc connected to said sleeve, a collar mounted on said shaft above said disc, a star wheel removably connected to the collar, an accelerating means carried by the collar, and a stationary cam race adapted to cooperate with said accelerating means whereby said accelerating means will accelerate the rate of travel of cans over said disc and maintain cans in spaced relation thereon. 110

6. In a can feeding and timing mechanism, the combination of a driven shaft, a sleeve rotatably mounted on said shaft, a driving connection between said shaft and sleeve, a feed- 120

ing disc connected to said sleeve, a collar mounted on said shaft above said disc, a star wheel removably connected to the collar above said disc, an accelerating means carried by said collar above said star wheel, and a stationary cam race adapted to cooperate with said accelerating means whereby said accelerating means will accelerate the rate of travel of cans over said disc and maintain cans in spaced relation.

7. In a can feeding and timing mechanism, a driven shaft, a sleeve journaled on said shaft, a driving connection between said shaft and sleeve for driving said sleeve at a different speed than said shaft, a feeding disc connected to said sleeve, means for adjustably positioning said disc and sleeve along said shaft, a collar mounted on said shaft above said disc, a star wheel removably connected to the collar above said disc, and an accelerating means carried by the collar above said star wheel and disc.

8. In a can timing and feeding mechanism, the combination of a driven shaft, a sleeve 25 rotatably mounted on said shaft, means for driving said sleeve from said shaft at a different speed than said shaft, a disc connected to said sleeve, means for adjustably positioning the sleeve and disc along said shaft, a collar 30 mounted on said shaft above said disc, a star wheel removably connected to the collar, an accelerating means carried by the collar, and a stationary cam race adapted to cooperate with said accelerating means whereby said accelerating means will accelerate the rate of travel of cans over said disc and maintain cans in spaced relation thereon.

9. In a can timing and feeding mechanism, a driven shaft, a disc journaled on said shaft, 10 means for driving said disc by said shaft but at a different speed, a star wheel mounted on said shaft above said disc, a spider mounted on said shaft above said star wheel, a plurality of radially movable fingers carried by said 15 spider, said fingers being adapted to space cans fed onto said disc and to accelerate the speed thereof, and means for adjustably positioning said disc along said shaft.

10. In a can timing and feeding machine, 50 a base, a bracket vertically adjustable on said base, a bearing in said bracket, a sleeve rotatably positioned in said bearing, a shaft rotatably journaled in said sleeve, means for driving said sleeve by said shaft at a different speed than said shaft, a feeder disc carried by said sleeve, and a spacing means carried by said shaft above said disc.

11. In a can timing and feeding machine, the combination of a base, a bracket vertically 55 adjustable on said base, a bearing in said bracket, a sleeve rotatably positioned in said bearing, a shaft rotatably journaled in said sleeve, means for driving said sleeve by said shaft at a different speed than said shaft, a feeder disc carried by said sleeve, a spacing 60

means carried by said shaft, means for guiding cans onto said disc and into contact with said spacing means, and means for accelerating the travel of cans over said disc carried by said shaft above said disc and spacing 70 means.

Signed at Los Angeles, California, this 15 day of June, 1927.
